UNITED STATES PATENT OFFICE.

HERMANN AHRENS, OF POSEN, GERMANY.

HOT-WATER HEATING SYSTEM.

1,026,236.

Specification of Letters Patent. Patented May 14, 1912.

Application filed December 5, 1910. Serial No. 595,725.

To all whom it may concern:

Be it known that I, HERMANN AHRENS, a subject of the German Emperor, residing at 3 Hardenburgstrasse, Posen, Germany, certified engineer, have invented certain new and useful Improvements in Hot-Water Heating Systems, of which the following is a specification.

This invention relates to a single pipe

- 10 water-heating device with pump action, in which suitable regulating valves are constructed in the descending supply pipes which enable a whole group of heating bodies to be regulated. This arrangement has 15 firstly the advantage that the numerous different regulating valves are dispensed with and secondly that the so-called short circuiting or diverting pipes become unnecessary, and thirdly none of the heating-body 20 connection pipes are connected with the ascending and descending supply pipes but directly with the regulating valves constructed in the descending supply pipes.

The regulating valves constructed in the 25 descending supply pipes consist of a combined cylinder slide and ball valve the inlet and the outlet opening in the cylinder slide being arranged in different planes, so that when the valve is raised the sectional area 30 of the inlet remains unthrottled and the sectional area of the outlet is only partially throttled, even when the largest quantity of water is diverted, so that the feeding of the rest of the heating bodies connected with 35 the supply is undisturbed and the reconveyance of the diverted hot water into the descending supply pipe can be effected without any stoppage. The invention does not 40 consist in the specific construction of the regulating valves but only in the combination of the regulating valves with the supply main of the system.

The invention is illustrated in the drawing, Figure 1 being a diagrammatical illustration of a heating arrangement. Fig. 2 a valve constructed in the descending pipe with inlet and outlet pipe connection and heating body pipe junctions indicated by dotted lines. Fig. 3 is a section on the line 50 3—3 of Fig. 2 through the valve-casing with a connection for one set of heating-bodies. Fig. 4 is a similar view to Fig. 3 showing connections for two sets of heating-bodies. Fig. 5 is a sectional view taken on the line 55 3—3 of Fig. 2, showing the valve in an open

position. Fig. 6 is a sectional view taken on the line 6—6 of Fig. 2 looking downwardly.

a is the ascending supply pipe running from the pump, *b* are the descending supply pipes. As shown by arrows in Fig. 2, the 60 tubular portion of the valve on the left is the inlet, that on the right the outlet, *c* indicates the heating bodies, *d* the return flow pipes.

The valve *e* has the same sectional area as 65 the descending supply pipe, and is provided with a distributing chamber *k* for one or more connections *i*. With the actual valve casing *f* inlet and outlet junctions *g* and *h* are connected.

i is a heating body junction which is situated on the distributing chamber *k*. In Fig. 4 a second heating body junction *i* is shown, a form of construction which is necessary in the arrangement according to Fig. 75 1 where two series of heating bodies are connected to one valve. The cylinder slide *m* that is guided on a pin *l* and secured against turning, is movable in the cylindrical casing *f*, which slide terminates in the direction of the valve spindle as a valve flange *n* adapted to rest on a valve seat *f'* of the casing *f*. The casing *f* is provided with an internally threaded cap *r*, through which works a screw threaded spindle *s*, having a 80 handle *t*, and by which the slide *m* is actuated. The opening *o* in the cylinder slide *m* that coincides with the opening in the inlet junction *g* is of such length that when the valve is raised to the highest point the 85 inlet opening in the valve casing is unthrottled, while the opening *p*, that coincides with the rectangular opening *u* in the outlet junction *h*, extends to the conical surface of the valve cone *n*, so that when the regulating device is raised the opening to the outlet junction *m* can be throttled to a certain extent by the part *q* in the side of the cylinder slide. As the opening *p* extends to the 90 valve cone *n*, when this is raised it frees the passage which is necessary for the diverting of the quantity of water throttled by the valve *n*. As will be seen from the drawing the opening to the outlet junction *h* is not 95 completely throttled even when the largest quantity of water is diverted.

The heating bodies *c* are provided in the lower part with cocks furnished with return-flow junctions, that open into the return-flow pipes *d*. By closing one or more 100

cocks of the return flow junctions one or more heating bodies can be disconnected, without the circulation in the heating pipes being thereby interfered with, that is to say if, for example, the first of three serially connected heating bodies is put out of connection, the second heating body can be kept in action. The circulating water in that case only flows through the upper part of the heating body and as water is a bad conductor of heat, the water in the first shut-off heating body below the upper passage remains quite cold.

Even when all the heating bodies of a group have to be shut off by the valve cocks arranged thereon in the lower return flow pipes, the circulation is in no way disturbed as the descending supply pipe cannot be shut off by the valve *e*. The water flowing out of the heating bodies *c* into the return flow pipes *d* and descending supply pipes *b* is mixed with that which flows through the partially throttled valve *e* and in fact through the outlet junction *h* through the connection of the return flow pipes *d* and the descending supply pipe *b* and enters the next connected groups of heating devices *c* and so on.

What I claim and desire to secure by Letters Patent is:—

A hot water heating system comprising in combination, a supply main communicat-

ing with the source of heat supply, heat radiating means, and a circulation control device interposed along said supply main and in communication with said heat radiating means, said circulation control device including a casing provided with a chamber having inlet and outlet ports for communication with said supply main, aligned to permit uninterrupted flow therethrough, and a chamber in communication with said first mentioned chamber adapted for communication with said heat radiating means, and a plunger, movable cross-wise the direction of current flow, adapted to close or open the communication between the said chambers of said casing, and provided with a wall adjacent to the said outlet port of said first mentioned casing, whereby said plunger may be moved to retard the current flow at said outlet port and divert the same into said second mentioned chamber, or to simultaneously close the said communication between the said chambers and allow uninterrupted passage through said first mentioned chamber.

In testimony whereof I have affixed my signature, in presence of two witnesses.

HERMANN AHRENS.
